UNITED STATES PATENT OFFICE.

EMIL TYDEN, OF EVANSTON, ILLINOIS.

DRY-PIPE SPRINKLER-SYSTEM ACCELERATOR.

Application filed February 15, 1926. Serial No. 88,167.

The purpose of this invention is to provide an improved construction of an accelerating device for a dry pipe sprinkler system. It consists of the elements and features of construction shown and described as indicated in the claims.

In the drawings:—

Figure 1 is a front elevation of the dry pipe main valve and connections comprising 10 devices embodying this invention.

Figure 2 is a vertical section of the accelerating device in a plane parallel with that of the elevation shown in Figure 1.

Figure 3 is a section at the line 3—3 on 15 Figure 1.

Figure 4 is a section at the line 4—4 on Figure 1.

Figure 5 is an enlarged detail section of 20 the valve controlling access of air pressure to the accelerator.

The drawings show the main valve casing A, with the water supply pipe, B, and pipe C, leading to the sprinkler head system, all 25 beyond the main water-controlling valve *a* in said casing, being referred to as the air pressure region of the system.

Connected with the air pressure region—the connection as shown being made by pipe, D, which is connected with, and leads from, 30 the cavity of the main valve casing,—is the accelerator device indicated as to its entirety by reference letter E, and comprising an attached part, F.

This accelerating device comprising a 35 casing having two chambers, 10 and 11, with which the air pressure region of the system communicates,—as hereinafter more particularly described,—by way of passages, 12 and 13, in said casing. These chambers communicate with the air pressure region of the system by means of a pipe, d, leading from 40 the pipe, D, by connection with the pipe limb, 46, hereinafter mentioned, said pipe, d, entering the casing, E, at a port *e*, which 45 opens into valve chamber 60*, wherein a valve, 60,—hereinafter more particularly described as to its mounting and operating connections,—co-operates with a valve seat, 61, having a port, 62, leading by way of passage, 63, into the chamber, 11. These chambers, 10 and 11, at the side of the casing E, opposite the part, F, have each an aperture in the outer wall, the aperture in the wall of the chamber 10, being a small one, as shown 50 at 15, that in the chamber, 11, being a large

one, as shown at 16; and upon this outer wall of the casing, E, there is applied a cap, e, having in its applied face a large cavity, 17, with its large aperture registering with the aperture, 16, in the wall of the chamber, 11, 60 and having a small aperture, 18, registering with the aperture, 15, in the wall of the chamber, 10. A duct, 19, connects the cavity, 17, with the aperture, 18. In the cavity, 17, there is mounted a diaphragm casing comprising two members, 20 and 21, between which a flexible diaphragm, 22, is clamped by its periphery. The diaphragm casing member, 21, has apertures, 21^a, for communication of the diaphragm chamber at one side 65 of the diaphragm through the duct, 19, with the chamber, 10; and the diaphragm casing member, 20, has apertures, 20^a, for communication of the diaphragm chamber at the other side of the diaphragm with the chamber, 11. 70

The pressure from the air pressure region of the system, it will be seen, reaches the chamber, 11, freely through the port, 63, so that changes in the pressure in said air pressure region will be experienced promptly in 80 said chamber, 11. But said pressure reaches the chamber, 10, by way of the passages, 13 and 12, and a fitting, H, which is interposed in the passage, 12, or between the same and its opening into the chamber, 10, the passage for pressure communication through the fitting, H, being restricted by a disk, h, interposed therein having an aperture, h¹, constituting the sole access of pressure from the 90 duct, 12, to the chamber, 10. The detail construction of this fitting will be understood from the drawing as comprising plugs, H¹, H¹, screwed into the opposite ends of the body member, H, of the fitting, each carrying 95 a perforated or woven wire strainer element, h², for guarding the restricted aperture, h¹, against choking by dust particles.

It will be seen that the diaphragm, 22, constitutes in effect an imperforate partition 100 separating the two chambers 10 and 11, so far as air communication between them is concerned, but subject to the communication of pressure from the one to the other by virtue of the pressures which reach the opposite 105 sides of the diaphragm through the respective apertures of the diaphragm casing member. In the diaphragm casing at the side toward the chamber, 11, there is mounted a plunger, 24, having an expanded head, 25, for 110

seating on the diaphragm, the plunger itself obtaining bearing and guidance in a bearing, 20^b, with which the diaphragm casing member is provided at its center projecting into the chamber, 11. The end of the plunger protrudes from said bearing for encounter with the inner end of an operating member, 30, which, as hereinafter more particularly described, extends air-tight through the wall 10 of the chamber, 11, for a function hereinafter more particularly explained.

The part, F, primarily affords a connection with the air pressure region of the system through which it is vented to the atmosphere; 15 and for that purpose it has a cavity or passage, 39, which opens at one end through a port, 41, at which the pipe, D, is connected, said pipe leading, as hereinafter mentioned, from the air pressure region of the system. 20 This port, 41, is controlled by a vent valve, 43, co-operating with a seat, 42, formed at the outer side of said port, 41. At the side of the passage, 39, said passage opens to atmosphere through the port, 40, whereby when the 25 valve, 43, is open, the pressure of the air pressure region of the system is freely and promptly vented and relieved.

The valve, 43, has its stem, 44, guided in a bearing seen at 48; and below that bearing 30 the casting, F, is chambered, as seen at 49, to accommodate a coiled spring, 51, which reacts between the lower side of said guide bearing, 48, and a collar, 50, screwed onto the lower end of the valve stem, 44, for initially holding the valve normally seated, and retracting it from open position to its seat on which it is adapted to be held by the air pressure of the system when the entire apparatus is "set." Incidentally the collar, 50, by fitting quite 35 closely approximately piston-wise in the stem chamber, 49, which is cylindrically bored, operates to prevent sudden retraction of the valve to its seat with a hammer blow thereon, and causes it on the contrary to seat with 40 comparatively slow movement without hammer. Below the spring chamber the part, F, has a cavity, 52, open at the lower end where it registers with an aperture, 26, in the flange, 27, which projects from the web of the hollow base, 28, of the casing, E, in which base 45 the weighted lever, 122, whose function is hereinafter described, is pivotally mounted and housed.

An important purpose of the construction, 50 being to cause the vent valve 43 to be opened by the movement of the operating part, 30, which results from the movement of the diaphragm, 22, upon the limited reduction of the pressure in the air pressure region of the system, is effected by the operating connections from the part, 30, to the vent valve stem, 44, which will now be described.

Said member, 30, is pivotally mounted in the lower wall of the chamber, 11, through 55 which wall it protrudes and is rendered air-

tight at its protrusion therethrough by means of a flexible sleeve, 90, whose upper end is clamped tightly about an enlargement, 91, of said operating member, 30, while the lower end is similarly clamped about the boss, 92, formed around the aperture through which said operating member protrudes from the casing. A convenient construction for the purpose is that shown, which consists of a plug, 95, which closes an aperture, 96, in the lower end wall of the chamber, 11, and which has at its upper side the boss, 92, mentioned, upon which the lower end of the flexible sleeve, 90, is made fast, said plug, 95, being secured in position closing the aperture, 96, by a screwed-in follower, 100. This follower, 100, is apertured to admit the upper forked part, 110, of a weighted bell crank lever, 111, said lever constituting a latch member having its latch nose, 112, engaging the flange, 105, which is formed at the lower end of the follower, 100, by counterboring its upper end portion. This bell crank lever is fulcrumed near its angle on a weighted lever, 122, which will be shortly described, and has its horizontal arm quite heavily weighted, as seen at 113, for effecting automatic engagement of the latch nose, 112, with the flange, 105, as described. Said end of the bell crank lever is engaged by the lower end of the operating member, 30, for disengagement of the latch nose by pivotal rocking of said operating member, which occurs when its upper end is moved inward by the inward thrust of the plunger, 24, which results from the reduction of pressure in the chamber, 11, consequent upon the reduction of the pressure in the air pressure region of the sprinkler system, which may be caused by the opening of a 100 sprinkler head. The weighted lever, 122, is fulcrumed near one end on pivot studs, of which one is indicated at 123, set in the wall or web, 28, of the casing, E, having its opposite end weighted as seen at 122^a for gravity movement for giving a powerful upward thrust by the shorter end of the lever, for opening the vent valve by connections. For this purpose there is pivotally connected to the lower end of the valve stem, 44, a swinging link, 130, which extends down through the open lower end of the chamber, 52, for engagement with a stud, 131, on the lever, 122, said link terminating in a cam projection, 130^a, at the upper limit of which there is formed an abrupt shoulder, 130^b, with which the stud, 131, collides after the initial downward swing of the weighted end of the lever has caused the stud, 131, operating on the cam terminal, 130^a, to swing the link, 130, a short distance to the right at its lower end; and upon the encounter of the stud with the shoulder 130^b the further down-swing of the weighted end of the lever causes the stud, 131, to give an upward thrust to the link, and thereby to the valve stem, 44, lifting the valve, 130.

43, from its seat, and accomplishing the venting which is the purpose of the connection.

Since such venting of the air pressure causing the main valve to be opened by the water pressure would cause the system to be flooded with water, and since in the absence of preventive means the water coming to occupy the entire air pressure region of the system would follow the conduit through which the 10 air pressure reaches the accelerator chambers, and flood those chambers, a further purpose of the construction is to cut off the communication from the air pressure region of the system to the accelerator after the vent valve is 15 opened as above described. The construction for this purpose will now be described.

The valve, 60, which controls access of the air pressure to the accelerator chambers, is held normally open by a spring device 66^m, 20 hereinafter more particularly described, which reacts for that purpose between a disk, 66^p, loose on the stem of the valve and stopped against a shoulder, 66^r, formed in the casing, E, and a similar disk, 64, which is clamped 25 rigidly on the valve stem between two parts, 65 and 66, of which the part, 65, is screwed into the part, 66, for clamping said disk between the shoulders of the two parts. The part, 66, is hollow from end to end, the part, 30 65, being screwed into one end closing the cavity and leaving the remainder of its length to the opposite end operating as a socket or guide bearing, as indicated at 66^a, for the end of the stem, 77, of a disk, 68, which is secured to the central portion of a diaphragm, 35 69, which partitions a diaphragm chamber formed by a recess, 70, in the outer surface of the left-hand upright end of the part, F, and a co-operating recess, 71, in the right-hand 40 face of an applied cap plate, 72, the two recesses being bounded by annular seats between which the margin of the diaphragm is clamped by bolts which secure the cap plate to the part, F. Said cap plate has at the 45 lower side a cavity, 73, opening at one end into the recess, 71, and at the lower end threaded for connection afforded by a pipe, 74, which leads from a part of the system to which the water pressure has access only when 50 the main valve is open, and which is connected for drainage when the water supply is cut off.

The cavity through which the diaphragm stem, 77, extends from its end guided in the 55 socket, 66^a, of the stem of the valve, 60, traverses at right angles the cavity, 52, and is bored at the end next to the diaphragm chamber to house and form a stop shoulder for a spring, 78, which reacts between said stop shoulder, 79, and the central hub of the disk, 68, for holding the diaphragm normally flat, and the stem, 77, out of touch with the end of the part, 65, of the stem of the valve, 60, which forms the bottom of the socket in which 60 the stem, 77, is guided.

The link, 130, is forked, as seen in Figure 4, at the upper part of its length, the fork clasping a lug at the under side of the collar, 50, for pivoting thereto, and the stem, 77, of the diaphragm, 69, is flat and extends between 70 the fork arms of the link, 130, said stem having a downwardly-extending lug, 77^a, which carries a cross-pin, 77^b, engaging slots, 130^a, in the two fork arms of the link, 130, so that the side swing of the link, caused by the 75 encounter of the stud, 131, with the cam terminal, 130^a, of the link, thrusts the stem, 77, into touch with the end of the member, 65, of the stem of the valve, 60. Simultaneously upon the venting of the system pressure by 80 opening the vent valve, 43, the water supply pressure enters and quite rapidly follows up the escaping air in the system, and, reaching the diaphragm, 69, through the pipe, 74, forces the diaphragm inward causing the 85 stem, 77, to thrust the valve, 60, fully to its seat, cutting off access of the system pressure, and thereby preventing the entrance of water which is following up the escaping air, into 90 the chambers of the accelerating device.

The same thrust of the stem, 77, pushes the link, 130, laterally, dislodging the shoulder, 130^b, from the stud, 131; whereupon the spring, 51, retracts the vent valve, 43, to its seat, preventing the waste of the water which 95 would otherwise occur through the vent port. The stress of the spring, 78, upon the stem, 77, transmitted to the link, 130, by the engagement of the cross-pin, 77^b, in the slots of the 100 fork arms of the link, holds the link stressed against the side of the stud, 131, at the position of the link for holding the valve, 60, closed; and the weighted lever, 122, pendent, holds the stud, 131, in the position for thus locking the valve, 60, closed until said pendent lever is manually lifted for resetting the apparatus after the system has been drained of the water, and it is desired to re-charge the air pressure region with air under pressure.

The specific detail form of the spring device, 66^m, for holding the valve, 60, normally open, is a crimped or corrugated spring tube commonly known as a "sylphon," which therefore encloses a chamber around the valve stem, 65. It will be understood that the "sylphon" device is itself open at both ends and that the disks, 64 and 66^p, do not close it airtight at either end; on the contrary, the "sylphon" is at all times, as necessary for its normal spring action,—open to discharge and entrance of air as it is compressed and reacts by expansion. It is therefore open to the air pressure derived from the air pressure region of the system which pressure passes by the valve, 60, for access to the accelerator chambers; and it will be understood that this air pressure serves to supplement the mechanical spring action of the "sylphon" for its purpose as described, of resisting the pressure derived through the diaphragm, 69, for seat-

ing the valve, 60, and for holding it seated, and reacting for opening said valve. For convenience of installing the valve, 60, with its two-membered stem, 65, 66, and this chamber spring device by mounting in the casing, E, there is provided the casing, 66^a, which encompasses and encloses the "sylphon" spring, 66^m, and affords a guide bearing for the hollow stem member, 66, and a stop for 5 the same in the direction of thrust of the sylphon spring, as seen in Figures 3, 4 and 5. This casing, 66^a, is screwed into a bored and threaded recess in the casing casting, E, and is thereby in position for entry of the hollow 10 boss at its left-hand end in which the stem member, 66, obtains seat and guidance in an aperture provided for it in the proximate wall of the part, F, when the latter is assembled in permanent relation to the casing, 15 E. The purpose of this specific construction is to effectually protect the valve, 60, from any access of water to it, or past it, into the accelerator chamber.

As mentioned above, the pipe, 74, for water 20 connection to the diaphragm chamber to operate the diaphragm, 69, for the purpose described must lead from a point in the system to which the water pressure has access only when the main valve is open for admitting 25 the pressure to the supply system, and since it is desirable that the diaphragm chamber should be drained to permit the diaphragm to recover its normal position and release the valve, 60, when the system is drained of 30 water, and is to be reset with proper pressure in the air pressure region, the pipe, 74, should lead from a point in the system which is open for drainage when the system is drained preparatory to resetting. Both these 35 conditions are met by connecting the pipe, 74, with the customary alarm pipe, 80, which leads from the interseat chamber, 84, of the main valve casing, in which there is shown the familiar construction for drainage of said 40 interseat chamber when the main valve is seated, and when the system is set for operation, consisting of the drainage connection, 85, for closing which there is provided a valve 86, which is held open when the main valve 45 is closed by the finger, 88, extending from the main valve through the main valve port for encounter with one end of the lever, 89, by which the valve, 86, is carried at the other end.

50 A very important consideration determining the construction for controlling the valve by which the system pressure is admitted to the accelerator chambers, is that it is liable to occur through inattention that the system air pressure by reason of some minor leak declines so slowly that the differentiation of pressure in the two chambers of the accelerator does not occur;—that is, the restricted communication between the two chambers is 55 equal in flow capacity to the leak; with the

result that this decline of pressure does not cause the accelerator to act for venting the system air pressure, and otherwise operating the device. In such case the leak continuing until the system air pressure becomes less than 70 the water supply pressure, the main valve opens and the system is flooded when there is no occasion,—that is, no fire to be extinguished; and in the absence of preventive means, the entire system being filled with 75 water, the water follows where the air pressure had previously and normally followed,—into the accelerator chambers, and that device becomes flooded, with the effect frequently of deposit of sedimentary material at various 80 places in the device, and in any event the accumulation of water in pockets from which there is no drainage and from which none can be readily provided. In such case it is practically necessary to dismount and disassemble the entire accelerator in order to 85 clean it of a deposit and restore its efficiency.

An important purpose of the construction shown in the drawings is to overcome this defect and prevent the undesirable flooding of 90 the accelerator. The specific means for this purpose consists in the pressure connection afforded by the pipes, 80 and 74 leading from the chamber, 84, of the main valve casing to the diaphragm, 69, connected as described for 95 closing the valve, 60, cutting off access of both air pressure and water pressure from the accelerator chambers.

It will be observed that the efficiency of the 100 construction shown for seating the valve, 60, under the circumstances indicated, depends upon the fact that the pressure which operates for seating it, being derived from the same 105 source as the pressure which normally operates for holding it open,—is thus operative by virtue of the excess of the area of the diaphragm over that of the valve. And it will be further observed that the result desired,—viz, the closing of the valve, 60, when the 110 main valve is opened so that from that opening there may not result access of water to the accelerator chambers,—will be obtained whether the pressure which operates through the open main valve in the chamber, 84, and thence through the pipes, 80 and 74, to the diaphragm, 69, is the remnant of air pressure in the system, or is the water pressure from the supply pipe; and that therefore the valve, 60, 115 will be closed upon the opening of the main valve, even though by oversight or intention the water supply may at that time be cut off by the closing of the shut-off valve which is customarily present (but not shown in the drawings) in the water-supply pipe, B; that is to say, primarily and fundamentally it is 120 the access of pressure, from whatever source from above the main valve, to the diaphragm which is afforded by the opening movement of the main valve, that accomplishes the result described.

I claim:—

1. In a dry pipe sprinkler system, in combination with a valve casing and a water-controlling valve therein, adapted to be held seated against the water pressure by the air pressure in the system, a device comprising means caused to operate for producing movement upon limited decline of pressure in the air pressure region of the system; a movable part caused to be moved by said means; an atmosphere vent port and a conduit leading thereto from the air pressure region of the system; a valve controlling said port positioned for being normally held seated by the pressure in the air pressure region of the system, and operative connections from said movable part for opening said valve against the air pressure of the system; means for automatically locking said valve at open position, and means operated by the water pressure, admitted as the result of venting the air pressure, for automatically releasing the locking means to cause said valve to be closed by the pressure resulting in the air pressure region, from the admission of the water pressure.

2. In a dry pipe sprinkler system, in combination with a valve casing and a water-controlling valve therein, adapted to be held seated against the water pressure by the air pressure in the system, a device comprising means caused to operate for producing movement upon limited decline of pressure in the air pressure region of the system; a movable part caused to be moved by said means; an atmosphere vent port and a conduit leading thereto from the air pressure region of the system; a valve controlling said port and yielding means for holding it normally seated; operating connections from said movable part for opening said valve; means for automatically locking said valve at open position, and means operating automatically upon the admission of the water pressure to the system for releasing said locking means to permit the vent valve to be closed by said normally closing means.

3. In a dry pipe sprinkler system, in combination with a valve casing and a water controlling valve therein, adapted to be held seated against the water pressure by the air pressure in the seat, a device comprising means caused to operate for producing movement upon limited decline of pressure in the air pressure region of the system; a movable part caused to move by said means; a port for venting the air pressure region of the system; a normally seated vent valve controlling said port; operating connections from said movable part for opening the vent valve upon decline of pressure in the air pressure region; automatic means for locking said vent valve at open position; a valve for controlling access of system air pressure to the first mentioned device; operating connections for clos-

ing said last mentioned valve comprising a part arranged for deriving valve closing movement consequent upon the venting of the air pressure, said operating connections being connected also for releasing the vent valve locking means.

4. In the construction defined in claim 1, a normally open valve controlling communication of the accelerating device with the air pressure region of the system, connections operated by said movable part for seating said valve in the movement for opening the vent valve, and means in said connections for locking said normally open valve at seated position while the vent valve is open; whereby air pressure to the accelerating device is automatically cut off when said system air pressure is vented to the atmosphere.

5. In the construction defined in claim 1, a weighted lever which is normally locked at upheld position of its weighted end; means operated by said movable part for releasing the locking means to permit the lever to fall; the connections for operating the vent valve being engaged with said weighted lever by means of which the falling of the lever forces open the vent valve, and the lever at fallen position locks the vent valve open; said connections comprising a link connected at one end with the vent valve stem and at the other end engaged by the lever for longitudinal thrust to open the vent valve, and for simultaneously swinging laterally about said pivotal connections; a valve which controls access of the system air pressure to the accelerating device, and means engaged with said link and connected with said last mentioned valve for closing said valve in the lateral movement of the link which occurs in the thrust movement by which the vent is opened.

6. In the construction defined in claim 1, a valve which admits the system air pressure to the accelerating device; the connections which are caused to operate by the movement of said movable part for opening the vent valve being adapted for simultaneously closing said air-pressure-admitting valve and comprising the means for locking the vent valve open; a chamber having a moving wall whose cavity communicates with a part of the system to which the water pressure has access only upon the main valve being open, and operating connections from said moving wall constituting the means for releasing the vent valve locking means; whereby the vent valve closes when the water pressure is admitted to the system, for preventing the water wasting at the vent port, and the water is simultaneously excluded from the accelerator.

7. In the construction defined in claim 1, a valve for controlling access of the system air pressure to the accelerating device, means for closing said valve connected for such closing

movement with the vent valve opening means, and means operated by the water pressure admitted upon venting the air pressure for automatically locking said valve 5 closing means in valve closing position.

8. The structure defined in claim 1 having an alarm operating water connection leading from a point in the main valve casing at which the intake of such connection is cut off 10 from both the air pressure and the water pressure when the main valve is seated and is open to the water supply pressure when the main valve is open; a valve which controls access of the pressure from the air pressure 15 region of the system to the chambers of the accelerating device; and means for seating said valve connected to said alarm operating water pressure connection.

9. In a dry pipe sprinkler system, in combination with a main valve therein mounted and connected for being opened by the water supply pressure and held seated by the system air pressure, said system having a drainage chamber which said main valve when 20 seated cuts off from both the water supply pressure and the system air pressure, and to which the water pressure has access when the main valve is opened; an auxiliary device and a conduit for communicating the system air pressure thereto; a normally closed vent valve in said conduit for venting the system pressure to the atmosphere; chambers in said auxiliary device to which said system pressure is communicated through said conduit; 25 mechanical connections which are actuated upon decline of the system air pressure for opening the vent valve and holding it open against the normally closing means; an element adapted to be moved by the water pressure, and connections from the drainage chamber for so moving said element, and operative mechanical connections from said 30 movable element to the means for holding the vent valve open for releasing said valve, said connections extending to and simultaneously operating said normally open valve for closing the same when the vent valve is opened.

10. In a dry pipe valve sprinkler system, in combination with a main valve casing and a main valve therein mounted and connected 35 for being opened by the water supply pressure and held seated by the system air pressure, said system having a drainage chamber which the main valve when seated cuts off from both the water supply pressure and the system air pressure, and to which the water pressure has access when the main valve is 40 opened; an auxiliary device having chambers; a conduit through which the system air pressure is communicated to said chambers; a valve controlling said communication; said conduit having an atmosphere vent port and a valve controlling said port; means brought 45 into operation by said auxiliary device for opening the vent valve and holding it open; an element adapted to be moved by fluid pres-

sure and connection from the drainage chamber for so moving said element, and mechanical operating connections from said movable element for releasing the vent valve from the means holding it open, and closing the valve 50 controlling access of pressure to the chambers of the auxiliary device.

11. In a dry pipe sprinkler system, in combination with the main valve casing and a main valve therein mounted and connected 55 for being opened by the water supply pressure and held seated by the system air pressure, said casing having a drainage chamber which said main valve when seated cuts off from both the water supply pressure and the system air pressure and to which the water pressure has access when the main valve is opened; an auxiliary device and a conduit for communicating the system air pressure thereto; a normally closed vent valve in said conduit for venting the system pressure to the atmosphere, said valve positioned with respect to its seat for being held seated by the system air pressure; chambers in said auxiliary device to which said system air pressure is communicated through said conduit, a normally closed shut-off valve for controlling the system air pressure connection to the chambers of the auxiliary device; mechanical connections which are actuated upon decline of the system air pressure for opening the vent valve and holding it open against said system air pressure; an element adapted to be moved by the water pressure, and connections from the drainage chamber for so moving said element, and operating mechanical connections from said movable element to the means for holding the vent valve open for releasing said valve, said connections extending to and simultaneously operating said normally open valve for closing the same when the vent valve is opened.

12. In a dry pipe sprinkler system in combination with a valve casing and a water-controlling valve therein adapted to be held heated against the water supply pressure by the system air pressure, said system comprising a chamber which the main valve when seated cuts off from both the water supply pressure and the air supply pressure; a conduit leading from the air pressure region of the system for connection with an auxiliary apparatus, said conduit having an atmosphere vent port, a valve controlling said port which is normally closed, means actuated upon decline of the system air pressure for opening the vent port-controlling valve, means for locking said vent port-controlling valve in open position, the connections for causing the closing of said atmosphere vent valve operating for that purpose by releasing said locking means.

13. In combination with a dry pipe sprinkler system, an accelerating device for hastening reduction of pressure in the air pres-

sure region of the system having a passage for communication with said region and adapted to be set in operation by decline of pressure in said region, the system comprising a conduit connected with said air pressure region for freely venting the pressure therein to the atmosphere; a vent valve controlling said conduit, said accelerating device comprising a chamber to which the pressure from 10 the air pressure region has access, a movable part mounted for movement in response to change in said pressure reaching said chamber, and mechanical connections from said movable part for causing the opening of said

atmosphere vent valve, said connections comprising a part extending from within said chamber and protruding air-tight out through the wall thereof, and other parts exterior to said chamber brought into operation for opening said atmosphere vent valve 15 by said protruding part, said exterior parts being accessible for manipulation both for reacting on said interior part and for causing the opening of said atmosphere vent valve.

In testimony whereof I have hereunto set 20 my hand at Los Angeles, California, this 28th day of January, 1926.

EMIL TYDEN.
